UNITED STATES PATENT OFFICE.

GEORGE E. WAIT AND JAMES R. WHITE, OF CHAGRIN FALLS, OHIO, ASSIGNORS TO THE OBER MANUFACTURING COMPANY, OF CHAGRIN FALLS, OHIO, A CORPORATION OF OHIO.

DESIGN FOR A SAD-IRON HANDLE.

42,344.

Specification for Design. Patented Mar. 19, 1912.

Application filed January 16, 1911. Serial No. 603,023. Term of patent 7 years.

To all whom it may concern:

Be it known that we, GEORGE E. WAIT and JAMES R. WHITE, citizens of the United States, residing at Chagrin Falls, in the county of Cuyahoga and State of Ohio, have jointly invented a new, original, and ornamental Design for Sad-Iron Handles, of which the following is a specification, reference being had to the accompanying drawings, forming part hereof.

Figure 1 is a side elevation of the handle showing our new design; and Fig. 2 is a top plan view of said handle showing our new design.

We claim:

The ornamental design for a sad iron handle as shown.

In testimony whereof, we hereunto affix our signatures in the presence of two witnesses.

GEO. E. WAIT.
JAMES R. WHITE.

Witnesses:
